(57) **CLAIM**

The ornamental design for a barrier panel, as shown and described.

DESCRIPTION

FIG. 1 is a front view of the barrier panel of my new design.

FIG. 2 is a perspective view of the barrier panel of my new design.

FIG. 3 is a left side view of the barrier panel of my new design. The right side view is a mirror image of FIG. 3; and,

FIG. 4 is a top view of the barrier panel of my new design.

The bottom view is a mirror image of FIG. 3.
